CLAIM

The ornamental design for a tire, as shown and described.

DESCRIPTION

FIG. 1 is a side perspective view of a first embodiment of a tire showing our new design, it being understood that the tread pattern is repeated throughout the circumference of the tire, the opposite side being the same as that shown; FIG. 2 is a front elevational view of the first embodiment of the tire;

FIG. 3 is a side elevational view of the left side of the first embodiment of the tire;

FIG. 4 is a side elevational view of the right side of the first embodiment of the tire;

FIG. 5 is an enlarged fragmentary view of FIG. 2 taken along lines 5-5;

FIG. 6 is a first transversal section view of the first embodiment of the tire taken along line 6-6 of FIG. 5;

FIG. 7 is a second transversal section view of the first embodiment of the tire taken along line 7-7 of FIG. 5;

FIG. 8 is third transversal section view of the first embodiment of the tire take along line 8-8 of FIG. 5;

FIG. 9 is fourth transversal section view of the first embodiment of the tire take along line 9-9 of FIG. 5;

FIG. 10 is a side perspective view of a second embodiment of a tire showing our new design, it being understood that the tread pattern is repeated throughout the circumference of the tire, the opposite side being the same as that shown;

FIG. 11 is a front elevational view of the second embodiment of the tire;

FIG. 12 is a side elevational view of the left side of the second embodiment of the tire;

FIG. 13 is a side elevational view of the right side of the second embodiment of the tire;

FIG. 14 is an enlarged fragmentary view of FIG. 11 taken along lines 14-14;

FIG. 15 is a first transversal section view of the second embodiment of the tire taken along line 15-15 of FIG. 14;

FIG. 16 is a second transversal section view of the second embodiment of the tire taken along line 16-16 of FIG. 14;

FIG. 17 is a third transversal section view of the second embodiment of the tire taken along line 17-17 of FIG. 14;

(Continued)

FIG. 18 is a fourth transversal section view of the second embodiment of the tire taken along line 18-18 of FIG. 14; FIG. 19 is a side perspective view of a third embodiment of a tire showing our new design, it being understood that the tread pattern is repeated throughout the circumference of the tire, the opposite side being the same as that shown; FIG. 20 is a front elevational view of the third embodiment of the tire;

FIG. 21 is a side elevational view of the left side of the third embodiment of the tire;

FIG. 22 is a side elevational view of the right side of the third embodiment of the tire;

FIG. 23 is an enlarged fragmentary view of FIG. 20 taken along lines 23-23;

FIG. 24 is a first transversal section view of the third embodiment of the tire taken along line 24-24 of FIG. 20;

FIG. 25 is a second transversal section view of the third embodiment of the tire taken along line 25-25 of FIG. 20;

FIG. 26 is a third transversal section view of the third embodiment of the tire taken along line 26-26 of FIG. 20; and,

FIG. 27 is a fourth transversal section view of the third embodiment of the tire taken along line 27-27 of FIG. 20.

The broken lines defining the shoulder tread ribs, sidewall,

and inner bead depict environmental subject matter that forms no part of the claimed design.
